UNITED STATES PATENT OFFICE.

MORRIS A. MARZYNISKI, OF BOSTON, MASSACHUSETTS.

PAINT-CAN.

SPECIFICATION forming part of Letters Patent No. 536,217, dated March 26, 1895.

Application filed May 19, 1894. Serial No. 511,791. (No model.)

To all whom it may concern:

Be it known that I, MORRIS A. MARZYNISKI, residing in Boston, county of Suffolk, and State of Massachusetts, have invented an Improvement in Paint-Cans, of which the following description, in connection with the accompanying drawings, is a specification, like letters and numerals on the drawings representing like parts.

10 This invention is an improvement in cans or like vessels of the class shown and described in another application, Serial No. 497,901, filed by me January 24, 1894, in which the can or receptacle employed for holding 15 paint, oil, lard, &c., is liquid tight when closed and whose cover can be utilized after the can has been opened.

My present invention has for its object to improve, simplify and cheapen cans of the 20 class referred to, and I accomplish my object primarily by making the can body in one piece of metal with an annular inwardly extended channel or groove located near the upper portion or top of the can body, and into 25 which is turned an inwardly extended edge or lip on a downwardly extended flange of the cover, which is fitted upon the outside of the can. The can body, above the groove referred to, is provided with a straight or vertical portion, provided with an inwardly turned 30 lip or rim to afford a bearing or supporting surface for a packing disk or ring, and this inwardly turned lip or rim may be provided with a depending flange, with which co-operates a depending double flange or fold on the 35 under side of the cover, which latter flange or fold serves to strengthen the can at its upper portion to enable it to withstand severe shocks or blows. These and other features of this 40 invention will be pointed out in the claims at the end of this specification.

Figure 1 is a vertical section of a can embodying this invention and such as commonly employed to hold paint, the thickness of the 45 material comprising the can being exaggerated to more clearly show the construction of the same and Fig. 2, a vertical section of the cover shown in Fig. 1.

The can body a , preferably of cylindrical 50 form, is made of metal, preferably tin, and is provided at its upper portion with an annular inwardly extended groove or channel a' ,

which may be of any desired or suitable depth and which is of sufficient width to receive an inwardly projecting annular lip or rim a^2 of an 55 annular depending flange a^3 of the cover a^4 .

The can body a above the groove or channel a' is provided with a vertical or straight portion 2, which, as herein shown, is bent inwardly to form the annular lip or rim 3 preferably provided with an annular depending flange 4, within which is fitted an annular depending fold or double flange 5 on the under side of the cover, and preferably formed by making an annular crease or bend in the top of 65 the cover so that the portion of the cover within the circumference of the said double fold is substantially flush with that portion of the top of the cover outside of or beyond the said double fold, whereby a smooth, flat top or upper 70 surface of the cover is obtained, which facilitates packing and affords a firm support for a can placed upon the said cover. The parts of the double flange or fold 5 are preferably pressed substantially in contact as represented in Fig. 2. An annular ring b of packing material is interposed between the cover 75 a^4 and the lip or rim 3.

The depending flange or double fold 5 fits against the depending flange 4 and materially strengthens the can at its top, so that it is able to resist severe blows and is not liable to become dented and leak.

In the can, herein shown and described the liquid tight effect is obtained primarily by the 85 inwardly projecting lip a^2 on the depending flange a^3 of the cover a^4 fitting into the annular groove or channel a' made in the body a of the can.

In practice, the can body with its inwardly 90 projecting groove or channel a' , its lip or rim 3 and flange 4 may be formed out of one piece of stock, and the liquid tight joint may be obtained without the use of solder.

In the drawings, the size of the groove a' 95 and of the lip or edge a^2 is exaggerated to more clearly show the construction. In practice, the vertical portion 2 above the groove a' will preferably be of smaller diameter than the body below the groove so that when the 100 cover is fitted to the can, the flange a^3 will be substantially flush with the body a of the can below the groove.

It will be understood that the lip a^2 is

straight and forms a continuation of the flange a^3 when the cover is first applied to the can body and is turned into the groove or channel a' after the cover has been fitted over the can body, and that the drawings show the said groove and lip very much larger than would be the case in the commercial article.

I claim—

1. A can for paint and like substances comprising a can body provided at its upper end with an inwardly projecting rim or lip, and a cover provided with a double fold fitted within the said inwardly projecting rim or lip, and having that portion within the double fold substantially flush with that portion beyond the said fold and with a depending outer flange fitted over the top of the can body, substantially as described.
2. A can for paint and like substances comprising a cylindrical body a provided with an annular groove or channel a' and with the vertical portion 2 above the said groove having the annular inwardly projecting rim or lip 3, and a cover provided with the flange 4 fitted over the vertical portion 2, the annu-

lar lip extended into said groove, and the double fold 5 on the cover fitted within the annular lip or rim, and having that portion within the circumference of the double fold substantially flush with the portion of the cover outside of the said fold, substantially as described.

3. A can for paint and like substances comprising a cylindrical body a provided with an annular groove or channel a' and with the vertical portion 2 above the said groove having the annular inwardly projecting rim or lip 3, provided with the depending flange 4, and a cover having the annular depending double fold to co-operate with the flange 4, and provided with the depending flange a^3 having the inwardly projecting lip extended into the groove a' , substantially as described.

In testimony whereof I have signed my name to this specification in the presence of two subscribing witnesses.

MORRIS A. MARZYNISKI.
